ARTHUR L. MILLER INVENTOR

BY

Lancaster Brome,
ATTORNEY

UNITED STATES PATENT OFFICE

143,844

DESIGN FOR A PORTABLE DESK LAMP

Arthur L. Miller, Newton, Mass., assignor to Sylvania Electric Products Inc., Salem, Mass., a corporation of Massachusetts

Application February 11, 1944, Serial No. 112,544

Term of patent 14 years

(Cl. D43—20)

To all whom it may concern:

Be it known that I, Arthur L. Miller, a citizen of the United States, residing at Newton, in the county of Middlesex and State of Massachusetts, have invented a new, original, and ornamental Design for a Portable Desk Lamp, of which the following is a specification, reference being had to the accompanying drawing, forming part thereof.

I claim:

The ornamental design for a portable desk lamp, as shown,

ARTHUR L. MILLER.
